DISPLAY DEVICE

Lillian G. Englar, Crestwood, N. Y.

Application October 31, 1938, Serial No. 238,105

5 Claims. (Cl. 40—126)

This application is a continuation in part of my prior application, Serial No. 47,268, filed October 29, 1935, which has matured into Patent No. 2,135,124.

5 The invention relates to display devices and particularly to those known as "dummies" in which a very close simulation of goods in a package is effected for use in window and show case displays and where the packing of real goods would otherwise be required.

10 The present invention seeks to present a simple and cheap yet rugged and durable box and lid simulation with easel or hanger having special utility for certain displays, to represent a complete package.

15 Another aim is to present novel specific forms of construction in such an article contributing to the facility of its manufacture and having other utility, as will appear from the disclosure 20 thereof hereinafter.

25 Additional objects, advantages and features of invention reside in the construction, arrangement and combination of parts involved in the embodiment of the invention, as will appear from the following description and accompanying drawing, wherein

30 Figure 1 is a plan of the back blank for the article, as shown in Figure 4 of my said prior application.

35 Figure 2 is a similar view of the top blank with edges added, corresponding to Figure 3 of my said application.

Figure 3 is a fragmentary plan of a completed package showing article units attached.

35 Figure 4 is a cross section of a completed package showing the manner of utilization of the invention in a complete dummy.

Figure 5 is a longitudinal section of the package.

40 There is illustrated in Figure 1 a blank 10 for the main back body portion of the article stamped from a good grade of pulp board or other suitable material, ordinarily about one sixteenth of an inch thick. On this there is set a top blank 11 of the same size, contour and thickness. The back includes a box outline or base portion 12 having the same boundary dimensions as that of the box to be simulated, and from one longitudinal edge of this the sheet material is 45 integrally continued to form a lid piece 13, the lateral edges 14 of which are relieved or formed inward of the end edges of the base 12 but parallel to an extension of the end edges 15 of the portion 12. A shoulder 16 is thus formed at 50 each side of the blank defining the junction 17

between the base 12 and the lid piece. The latter is of a size corresponding to that of a lid required to cover a box of the same area as the base 12. Ordinarily the lid piece is a continuation of the base 12, without any weakening line 5 between them, but if desired, a hinge connection may be formed in any well known manner, except across an easel piece or leg 18, which is cut on three sides 19 from parts of both the lid back 13 and base 12, without any weakening cuts or 10 creases to provide for folding thereof except at the fourth side, which remains undetached, but may be creased sufficiently at its base 20 to facilitate its hinged movement as required. As formed in the blank illustrated, the easel leg before being pushed from the plane of the sheet toward its operative position, is inverted, its pivot base being on the base 12, a distance inwardly of the line of junction 17 between the base 12 and lid piece 13. The leg extends across the line 17 into 15 the lid piece a substantial distance. Formed transversely in the leg 18 there is a narrow slot 21. Formed in the base 12 below the leg 18 and joined integrally to the base 12 on a line 22 parallel to and spaced from the line 17 toward the 20 center of the base 12, there is a stay piece 23 cut out on three sides to swing out from the base 25 on the line 22, and to connect with the leg 18. At its extremity a longitudinally projecting dovetail tongue 24 with rounded corners is formed on 30 the stay piece 23, having a width at its outer part slightly greater than the length of the slot 21, but adapted to enter the slot by a slight 35 springing of the material of the leg 18, and tongue, and be retained therein with sufficient security to brace the leg 18 in extended position for use as will be explained.

The parts 18 and 23 are cut on three sides with suitable dies in the desired form, but left 40 flush and frictionally held in the original piece throughout manufacture of the complete dummy, in which the article as described is to be used, and the easel parts are only drawn out and connected at the time and place when and where they are required for use in a display. The back 45 piece as illustrated in Figure 1 is backed by the top blank 25, which is of the same size and contour, giving stiffness and thickness to the assembly. The material of these two pieces should be of good material not easily bent or broken 50 in the handling to which such articles are subjected. The top blank includes a top body plate 26, and lid piece 27 trimmed in alignment with the edges of the base 12 and lid piece 13. At each 55 side of the plate 26 an end piece 28 is formed

consisting of one or more superposed narrow strips of pulp stock or other cheap material, the quality of which is immaterial, stapled to the end edges of the plate 26, to form a body for a representation of the top edge portions of end walls of a standard container such as a cigar box. These built up ends may now be covered with the usual ornamental and advertising tape customarily applied to the edges of cigar boxes, or this covering may be omitted until after placement of the article units as will be described.

A group of article units is mounted on the body plate and secured thereto, each unit consisting of an embossed representation 29 of an article which in the present instance is a cigar. These embossings as shown are of pressed paper suitably textured and colored and otherwise made up to represent a cigar as closely as possible although only the top portion need be reproduced, and the embossings are therefore comparatively shallow, and U-shaped in cross section. Each embossing is inserted in a section of sleeve or tubing 30 of flexible transparent sheet material such as nitrocellulose as commercially available, slightly longer than the embossing. Other methods of producing the units may be employed. The jacketed members are then laid side by side beginning at one end of the plate 26, the first unit being laid beside the built-up end piece 28.

The ends of the sleeves projecting beyond the embossing are stapled to the front edge portion of the plate 26 as at 31, and to the lid piece 27 as at 32, just beyond the line of its junction with the plate 26. This leaves an area beyond the staples on the lid piece within which a lid plate 33 may be stapled to the lid pieces 27 and 13. The plate 33 is the full size of the lid parts 13 and 27. The end portions of the sleeves 30 projecting beyond the front edge of the plate 26 are then trimmed flush with the plate edge and a front wall edge representation 34 then stapled to the front edge of the plate 26 and upon the ends of the sleeves, flush with the front edge of the plate. The edge 34 is of less height than the raised end edges 28 from the mean plane of the device. Edging tape 36 is then applied over the raised edge piece 34, and over the outer edges of the lid piece 13 and lid plate 33 as at 37, thus securing these together upon the intervening top lid piece 27. If the end wall edges 28 have not been covered before placing the units, those edges are also now covered with appropriate material 38 at this time. Application of a label 35 to the top face of the lid plate 33 completes the simulation of a complete full package of articles, as viewed from above, or partly from one side. The label extends to or slightly over the edges of the lid border 36, and to or slightly beyond the inner edge of the lid plate 33 with a white portion forming the edge portion, and thereby simulates the top edge of a box adjacent the hinge of the lid. If applied before the edging on the lid members, the label element may be wider and so form a more perfect simulation of the box at the inner corners, but it is an advantage of my method that to the superficial glance, if the label stops short of the raised end wall members 28, it will not be observed, and if noted on more particular examination by the public, no objectionable detriment to the effect is suffered.

A semi-circular or other U-shaped cut 39 is made in the upper central edge portion of the lid back 13 within which an aperture 40 is made,

forming a tab 41 which may be turned outward and utilized as a hanger, the aperture being engaged over the head of a nail or other support on a wall or other surface, vertical or inclined. It is an advantage of this arrangement and construction that if engaged on a vertical or an inclined surface with the sides of the plate 26 abutting the sides of the lid plates snugly, an appearance of a large number of full boxes of indefinite depth is created, and more so if some element is provided concealing the sides of the group.

Scored or pressed lines as at 25 may be formed in the blanks to stiffen them and for other uses.

The plate 26 may be colored to produce the effect of shadow below the article units, as is practiced generally with dummy displays.

I claim:

1. In a display device of the character described, a substantially flat rectangular body portion having an area and contour corresponding to the area of a container to be represented, and an integral lid extension therefrom in the same plane having an area and contour corresponding to that of a lid for such container, raised edges on the three outer edges of the first named body portion simulating box edge portions, and a multiplicity of article units fixed on the said body portion.

2. The structure of claim 1 in which the body member and its extension comprise superposed board elements secured together in fixed relation, the lower one having an easel leg cut on three sides therein extending from the lower body portion into the said lid extension and arranged so that it may swing outward at its upper part, and a stay element cut on three sides in the lower part of the said body portion and arranged so that it may swing outward to meet the easel leg when in operative position, and interlocking parts on the leg and stay.

3. The structure of claim 1 in which the said extension is of less width than the body portion, said raised edge portions at the lateral edges of the body portion being higher than the third raised edge.

4. The structure of claim 1 in which the said body portion and lid extension comprise a board member, and said article units comprise cigar shaped members, a transparent sheeting enclosing said units and projecting therebeyond at top and bottom, and being fastened directly to the board member at its front edge and to the lid extension, one of said raised edge portions being built over the projecting portions of said sheeting, and a lid plate element secured over the opposite projecting portions of said sheeting, and over said lid extension.

5. The structure of claim 1 in which the said body portion and lid extension comprise a board member, and said article units comprise cigar shaped members, a transparent sheeting enclosing said units and projecting therebeyond at top and bottom and being fastened directly to the board member at its front edge and to the lid extension, one of said raised edge portions being built over the projecting portions of said sheeting, and a lid plate element secured over the opposite projecting portions of said sheeting and over said lid extension, said plate being of less altitude from the mean plane of the display device than the said lateral raised edge portions on said body portion.

LILLIAN G. ENGLAR.
